UNITED STATES PATENT OFFICE

2,463,268

SPRING HOBBYHORSE

William C. Handley, Chicago, Ill.

Application October 1, 1945, Serial No. 619,628

4 Claims. (Cl. 272—55)

1

This invention relates to an improved toy in the nature of a hobbyhorse. More specifically, it relates to an improved method for anchoring the principal spring member of a spring hobbyhorse.

The principal object of the invention is to provide a toy device of the type herein described having an almost indefinite life by reason of the elimination of a method of mounting the principal leaf spring which has heretofore resulted in the weakening and eventual fracture of the spring at the mounting point. The fastening structure disclosed provides a firm assembly which does not weaken the spring structure appreciably at any point and does not impair the strength of the principal spring to any degree whatever.

A further object of the invention is to provide a toy assembly of the type herein described having improved operating characteristics and therefore capable of furnishing a greater degree of enjoyment to the user. A still further object is to provide a simple and economical toy device.

In the accompanying drawing,

Fig. 1 is a perspective view of the spring hobbyhorse embodying the improved construction;

Fig. 2 is a partial section taken at the line 2—2 of Fig. 1 and showing the details of the principal spring anchorage; and

Fig. 3 is a detailed sectional view taken at the line 3—3 of Fig. 2.

In the preferred embodiment of the invention, a base for the hobbyhorse comprises two cross arms 1 and 2, generally formed from wood, and a connecting member 3. Cross members 1 and 2 are rabbeted to receive the ends of connecting member 3 and this member and the rear cross arm 2 are rigidly fastened together by means of a bolt 4. For reasons explained in greater detail below, connecting member 3 is preferably fabricated from spring steel stock.

The principal spring member 5 is roughly U-shaped and is composed of a suitable spring steel material, such as silicomanganese steel. The lower and shorter leg overlaps base connecting member 3 and is fastened thereto by means of a bolt 6. A U-bolt 7 serves to anchor leaf spring 5 to front cross arm 1. Together with pin 8 which extends through a hole 9 in the forward end of connecting member 3, U-bolt 7 also serves to fasten connecting member 3 to front arm 1. As shown in greater detail in Fig. 3, the bottom surface of the rabbet cut in cross arm 1 is rounded to permit a limited rocking action of base connecting member 3 as the latter flexes.

2

A suitable seat 10 is mounted upon the upper leg of leaf spring 5 at its end, as shown in Fig. 1, and a suitable standard 11 in the form of a horse's head may be fastened to seat 10 and a handle 12 may be carried by the standard. A foot rest 13 is furnished by suitably formed metal pieces clamped to spring 5 by means of a bolt 14.

To operate the device thus described, the child sits upon seat 10, places his feet upon the foot rest 13, grasps handle 12, and proceeds to ride up and down over gradually increasing distances as the manipulation of his body, timed to the natural oscillatory period of the spring system, alternately stores energy in the spring system and permits the expenditure thereof in the return upward movement. In view of this mode of operation, it will be apparent that unless the flexing of the spring member is distributed throughout a substantial portion of the entire length of the spring system, fracture of the spring would result in a relatively short time due to fatigue of the metal. In hobbyhorses of this type heretofore available, the principal spring member was fastened to the front cross arm by means of a single bolt which passed through a hole punched or drilled through the spring member itself. Removal of this metal, together with distortion of the metal immediately surrounding the hole, resulted in the weakening of the spring at this critical point and failure with possible injury to the child frequently resulted. The full strength of the spring member is preserved unimpaired by use of the anchorage construction herein described. Also, the entire spring system, beginning at the seat 10 and continuing to the end of connecting member 3 at cross arm 2, flexes as the seat is depressed. Thus, the spring load is well distributed throughout the length of a uniformly strong spring system.

While the provision for limited rocking action of the leaf springs upon cross arm 1, as described, is desirable, it is not indispensable to satisfactory operation of the device. Since the cross arms 1 and 2 are not connected except by the flexible spring member 3, both of these arms move with the flexing of the spring, but it will be apparent that such movement is not entirely unhampered and is undesirable because of the accompanying rubbing action of the under surfaces of the cross arms against the floor which may mar the finish or, if placed upon a rug, the action may wear a hole in the floor covering. Also, it will be understood that the bottom surface of the rabbet in cross arm 2 may be curved and a U-bolt and pin used to fasten the parts together in a

manner similar to that described in connection with the anchorage at cross arm 1. Further, the rabbeting of the cross arms may be dispensed with, the spring strips being mounted upon the normal upper surface of the cross arms which, preferably, may be rounded to permit the rocking movement.

It will be apparent that a single unitary leaf spring may be employed in place of the composite member consisting of spring 5 and connecting element 3. Also, although connecting member 3 is preferably composed of a flexible material so that a portion of the spring strain is carried by this member, this member may be of rigid construction and the leaf spring 5 relied upon to carry the full load.

I claim:

1. In a spring hobbyhorse, a rear base cross arm and a front base cross arm, a connecting member extending between said cross arms and having the rear extremity thereof fastened to said rear cross arm, a pin projecting upwardly from said front cross arm and extending substantially through the front extremity of said connecting member, a leaf spring engaging a portion of said connecting member and extending forwardly therefrom and carried upwardly and back over said connecting member, and means for supporting said leaf spring, said means comprising means for positively fastening the extremity of said leaf spring to said connecting member and a U-bolt straddling said leaf spring a short distance from the extremity thereof and straddling said connecting member and passing downwardly through said front cross arm and clamping said spring and said connecting member thereto.

2. In a spring hobbyhorse, spaced cross arms adapted to rest upon a supporting surface, a U-shaped leaf spring system arranged in a vertical plane with one leg thereof below the other leg and disposed upon said cross arms, the surface of the cross arm nearest the bend of said spring system engaging said spring system being rounded to permit said spring system to rock upon the cross arm as the spring system is flexed, and a U-bolt clamping the lower leg of said spring system to the rounded surface of the cross arm.

3. In a spring hobbyhorse, a front and a rear base cross arm, a leaf spring connecting

member extending between said cross arms, the rearward extremity of said connecting member being fastened to the rear cross arm, a pin extending upwardly from the front cross arm substantially through the thickness of said connecting member at the forward extremity thereof, the surface of said front cross arm engaging said connecting member being rounded to permit said connecting member to rock upon the front cross arm as the connecting member is flexed, a retroflected leaf spring arranged in vertical position and having one leg below the other leg and engaging said connecting member, and means for anchoring the lower leg to said connecting member and front cross arm, said means comprising means for fastening the extremity of said lower leg to said connecting member at a point between said cross arms and a U-bolt straddling said lower leg and said connecting member and passing downwardly through said front cross arm.

4. In a spring hobbyhorse, a front and a rear base cross arm, a leaf spring connecting member extending between said cross arms, the rearward extremity of said connecting member being fastened to the rear cross arm, a pin extending upwardly from the front cross arm substantially through the thickness of said connecting member at the forward extremity thereof, a retroflected leaf spring arranged in vertical position and having one leg below the other leg and engaging said connecting member, and means for anchoring the lower leg to said connecting member and front cross arm, said means comprising means for fastening the extremity of said lower leg to said connecting member at a point between said cross arms, and a U-bolt straddling said lower leg and said connecting member and passing downwardly through said front cross arm.

40 WILLIAM C. HANDLEY.
